UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed August 4, 1921. Serial No. 489,763.

To all whom it may concern:

Be it known that I, THOMAS E. PRAY, a citizen of the United States, residing at Chicago, in the county of Cook and State 5 of Illinois, have invented an Improvement in Mining Machines, of which the following is a specification.

This invention relates to attachments for mining machines of the class adapted to be 10 moved along a mine wall to cut a horizontal kerf. The object of this invention is to provide an improved support for mining machines of the class described whereby the kerf may be cut in a plane somewhat higher 15 than the normal cutting plane of such machines.

The invention may best be understood by referring to the drawings in which Figure 1 20 is a plan view of the support with the mining machine removed therefrom, and having a portion of the top plate broken away.

Figure 2 is a view showing the support in longitudinal section, with a mining machine mounted thereon, and shown in full 25 lines in their lowermost position. In this figure the support and mining machine are also shown in dotted outlines to indicate their fully raised position.

Figure 3 is a detail view of the lifting 30 jack, partly in cross section.

Coal mining machines of the class described are usually moved along the face of the mine wall by means of a flexible draft device anchored at a distance from the machine. One of such machines is illustrated 35 in the drawing, and comprises a body portion A, containing a motor and operating mechanism, and having a cutter bar B, adapted to cut the kerf at or near the bottom of the seam or vein of coal, and a power 40 operated draft device C, associated with a suitable winding drum D.

In mining coal it is often found desirable 45 to cut the kerf along a seam of dirt or other foreign material above the normal cutting plane adjacent the mine floor. Furthermore, the dirt seam may be of variable height so that it is desirable to change the height of the cutter bar while making the cut.

In the present invention I provide a support 50 which may be attached to the bottom of the main frame A of the mining machine by any suitable means, such as bolts 3, 3. This support comprises a top plate 55 4, and a bottom plate or base 5, connected

by two pairs of pivoted supports 6, 6 and 7, 7 at opposite ends thereof and arranged to maintain said upper and lower members in parallel relation with each other. Said bottom plate 5 preferably has its side margins 8, 8 and end margins 9, 9 curved upwardly as shown so as to readily pass over the mine floor without accumulating loose material thereon.

Means for raising and lowering the support comprises a link 10 pivotally connected at one end to the top plate 4, and at the other end to a movable head 13 of a ratchet device, such as a lifting jack 11 lying horizontally on the bottom plate 5 and having 60 its foot 12 engaging the rear margin 9 of said bottom plate. Said jack may be of any approved pattern, and may be secured in place by any suitable means such as a clamp 14 attached to the bottom plate 5. 65 The pivotal connection of the lower end of the arm 10 and the movable head 13 comprises a pivot pin 13^a. Said head 13 has a downwardly extending portion 15 adapted to bear against the bottom plate 5. 10205 10210 10215 10220

horizontal pressure from the jack is required in order to raise the support. When the head 13 of the jack 11 is actuated in raising the support the hooked ends 18, 18 of arms 17, 17 move therewith until the limit of movement of said arms is reached. Thereafter, the hooks 18, 18 become disengaged from the pivot pin 13^a, but remain in position to receive the pivot pin when the support is again lowered.

By means of the device above described, a mining machine may be raised or lowered as desired. The machine and support require a minimum overall height, so that they may be transported from place to place as a unit under a low roof in the usual manner.

Another advantageous feature of my device is the arrangement whereby the mining machine may be raised from its lowermost position by its own power. This is accomplished by anchoring the power driven draft rope C in advance of the machine and support, so that when the rope is wound in, the plate carrying the machine will be swung upwardly and forwardly about the pivoted links 6, 6 and 7, 7 into raised position as shown in Figure 2.

Having described my invention, what I claim as new and desire to cover by Letters Patent, is:—

1. In combination with a kerf-cutting element having power actuated flexible draft mechanism mounted on and movable therewith, a support for said element, and means on said support adapted to coact with said draft mechanism for elevating said element.
2. In combination with a kerf-cutting mining machine having power actuated draft mechanism, a support for said machine and means on said support comprising two pivoted parallel members adapted to coact with said draft mechanism for elevating said machine.
3. In combination with a kerf-cutting mining machine having power actuated draft mechanism, a support for said machine, means on said support adapted to coact with said draft mechanism for elevating said machine, and spring means attached to said support to assist the initial upward movement of said support.
4. In combination with a kerf-cutting mining machine having power actuated draft mechanism, a support for said machine, means on said support adapted to coact with said draft mechanism for elevating said machine, means for holding said support in elevated position, and spring means adapted to retard the downward movement of said support.

5. In combination with a kerf-cutting mining machine, a support for said machine comprising two members movable vertically with respect to each other, elevating mechanism on said support comprising two pivot-

ed parallel members, a horizontally disposed ratchet device, mounted on one of said movable members, and a pivoted link connecting said ratchet device with the other movable member.

6. In combination with a kerf-cutting element having power actuated draft mechanism mounted on and movable with said cutting element, a support for said element adapted to coact with said draft mechanism for elevating said element, and means limiting the elevating movement at a predetermined position.

7. In combination with a kerf-cutting mining machine, a support for said machine comprising two members movable vertically with respect to each other, elevating mechanism on said support comprising two pivoted parallel members, a horizontally disposed ratchet device mounted on one of said movable members, a pivoted link connecting said ratchet device with the other movable member, and spring means attached to said support to assist the initial upward movement of said support.

8. In combination with a kerf-cutting mining machine, a support for said machine comprising two members movable vertically with respect to each other, elevating mechanism on said support comprising two pivoted parallel members, a horizontally disposed ratchet device mounted on one of said movable members, a pivoted link connecting said ratchet device with the other movable member, and spring means adapted to retard the downward movement of said support.

9. In combination with a kerf-cutting mining machine, a support for said machine comprising two members movable vertically with respect to each other, elevating mechanism on said support comprising two pivoted parallel members, a horizontally disposed ratchet device mounted on one of said movable members, a pivoted link connecting said ratchet device with the other movable member, and means limiting the elevating movement at a predetermined position.

10. In combination with a kerf cutting element provided with a flexible draft device adapted to extend at various angles to fixed abutments to produce a horizontal draft on said cutting element and operable normally for feeding the same, a support for said cutting element comprising a base adapted to engage the ground, and elevating means interposed between said base and said cutting element operable by relative horizontal movement of said cutting element and said base.

11. In combination with a kerf cutting element provided with a flexible draft device adapted to extend at various angles to fixed abutments to produce a horizontal draft on said cutting element and operable normally for feeding the same, a support

for said cutting element comprising a base adapted to engage the ground, elevating means interposed between said base and said cutting element operable by relative 5 horizontal movement of said cutting element and said base, and tension means co-acting between said base and said cutting element.

12. In combination with a kerf cutting element provided with a flexible draft device adapted to extend at various angles to fixed abutments to produce a horizontal draft on said cutting element and operable normally for feeding the same, a support 10 for said cutting element comprising a base adapted to engage the ground, elevating means interposed between said base and said cutting element operable by relative horizontal movement of said cutting element and said base, and tension means co-acting between said base and said cutting element during the initial upward movement of said cutting element.

13. In combination with a kerf cutting element provided with a flexible draft device adapted to extend at various angles to fixed abutments to produce a horizontal draft on said cutting element and operable normally for feeding the same, a support 25 for said cutting element comprising a base adapted to engage the ground, elevating means interposed between said base and said cutting element operable by relative horizontal movement of said cutting element and said base, and supplementary actuating devices for controlling the relative movement of said cutting element and said base.

14. The combination with a kerf cutting element provided with suitable flexible feeding and guiding devices for moving said machine during the cutting operation, of a support for said machine movable with the latter during its cutting operation, and adapted to raise the latter to 40 cut in a plane higher than its normal cutting plane, said support comprising a base,

and a movable connecting element arranged to produce relative vertical movement between said base and said cutting machine 50 when the latter is moved longitudinally of said base in co-operation with its flexible feeding element.

15. The combination with a kerf cutting mining machine provided with suitable flexible feeding and guiding devices for moving said machine during the cutting operation, of a support for said machine movable with the latter during its cutting operation, and adapted to raise the latter 55 to cut in a plane higher than its normal cutting plane, said support comprising a base, a movable connecting element arranged to produce relative vertical movement between said base and said cutting machine 60 when the latter is moved longitudinally of said base in cooperation with its flexible feeding element, and supplementary actuating mechanism for controlling the relative movement of said cutting machine 65 and said base.

16. In combination with a kerf cutting member having a substantially horizontal cutting arm, a support for said cutting member comprising a base member and connecting means including supporting devices at a plurality of points between said cutting member and said base member arranged to be simultaneously extended vertically by relative horizontal movement between said cutting member and said base member, and flexible draft mechanism mounted on one of said members adapted to be anchored to a fixed abutment and arranged to coact with said cutting element 75 to move it horizontally respective to said base whereby said cutting element may be raised into various positions with its cutting arm maintained in a substantially horizontal plane.

Signed at Chicago, Illinois, this 2nd day of August, 1921.

THOMAS E. PRAY.
